UNITED STATES PATENT OFFICE.

ISRAEL MARCUS, OF WINTHROP, MASSACHUSETTS.

GROUND-CONNECTOR.

1,205,374.

Specification of Letters Patent. Patented Nov. 21, 1916.

Application filed January 24, 1916. Serial No. 74,024.

To all whom it may concern:

Be it known that I, ISRAEL MARCUS, a citizen of the United States, residing at Wintrop, in the county of Suffolk and State of Massachusetts, have invented certain new and useful Improvements in Ground-Connectors; and I do declare the following to be a full, clear, and exact description of the invention, such as will enable others skilled in the art to which it appertains to make and use the same.

This invention relates to new and useful improvements in ground connectors of the type clamped to embrace a pipe or suitable ground conductor, and adapted to make a good electrical connection therewith.

The objects of this invention are to provide a simple, practical, and efficient connector which is adapted to be adjustable, so that the same may be connected to various sizes of conductors, and which will form a very secure connection therewith.

A further object of the invention is to provide a device which is simple and durable in construction, inexpensive to manufacture, and one which will be very efficient in operation.

With these and numerous other objects in view, my invention consists of the novel features of construction, combination and arrangement of parts which will be herein referred to and more particularly pointed out in the specification and claim.

In the accompanying drawings: Figure 1 is an end view of the connector showing the same applied to a pipe; Fig. 2 is a central vertical section; Fig. 3 is a side elevation; Fig. 4 is a similar view to Fig. 3, taken from the opposite side of the connector, and Fig. 5 is a horizontal section taken on the line 5—5 of Fig. 1.

In describing my invention, I shall refer to the drawings in which similar reference characters designate corresponding parts throughout the several views, and in which the numeral 1 designates a flexible metallic strip, of equal width throughout its entire length, and which has adjacent one end 2, a plurality of longitudinally extending spaced apertures or openings 3. The other end 4 of the metallic strip 1 has a single aperture or opening 5 therethrough disposed a predetermined distance from the same. A portion of the strip between said opening 5 and the end 4, adjacent said end 4 is bent upwardly substantially U-shaped, having its

side edges 6 lying parallel and disposed in a plane substantially at right angles to the plane of the remaining side edges of the strip 1.

The flat metallic strip 1, owing to its flexibility, is adapted to surround the pipe or other suitable conductor 7, as clearly shown in Fig. 2 of the drawings, and is adapted to have the aperture 5 adjacent the end 4 of the same disposed in alinement with one of the apertures 3 through the opposite end 2 of said strip. Owing to the fact that the end 2 of the strip is provided with a plurality of longitudinally spaced openings, it will be obvious that this metallic strip will be adjustable to various sizes and shapes of suitable conductors, as the single opening 5 at one end of the strip may be disposed in alinement with any one of the various openings 3 in the opposite end of the strip, in accordance with the size of the conductor which it surrounds.

When in position around a conductor, as shown in Fig. 2 of the drawings, and so disposed that the aperture or opening 5 is in alinement with one of the openings in the opposite end of the strip, a pair of side plates 8 and 9 are adapted to be positioned on the outer surface of said ends of the band, the side plate 8 being disposed adjacent the end 4 of the band, while the side plate 9 is positioned adjacent the opposite end 2 of the same. The side plates 8 and 9 are provided with centrally disposed apertures 10 and 11, which are adapted to align with the corresponding openings 5 and 3 in the opposite ends of the strip, when in position. The opening 11 which is disposed through the side plate 9 is internally screw threaded for a purpose to be hereinafter more fully set forth.

The side plates 8 and 9, have projecting from their free edges, obliquely inclined outwardly extending flanges 12 which are adapted to be positioned adjacent the top of the conductor 7, as clearly shown in Fig. 2 of the drawing. The side plates 8 and 9, and the projecting flanges 12 of the same are substantially the same size when positioned at opposite ends of the metallic strip, and the flanges of the same will extend downwardly an equal distance along the outer surface of the strip 1.

The side plates, on adjacent ends of the band, are adapted to hold the said band around the conductor 7 by means of a headed

screw 13, which is adapted to be positioned through the alining openings in the band and plates and disposed in threaded engagement with the opening 11 through the side plate 9. This screw 13 has a lock nut 14 on its outer end, which is adapted upon being moved thereon, to lock the side plates and ends of the band together to securely clamp the said band around the conductor. 10 When this band is positioned as above described, it will be obvious that the end 4 of the same will project a certain distance above the opposite end 2 thereof, and owing to the fact that the side edges of said projecting end are upturned to form a substantially U-shaped portion, the same is adapted to act as a terminal so that it may be easily clamped around the end of a lead wire.

The projecting flanges 12 on the lower edges of the side plates 8 and 9 space said plates from coming in close proximity to the conductor 7 when the parts are clamped together.

The above description, and the accompanying drawings, describe and illustrate a ground clamp, which is formed of a very simple and efficient arrangement of a flexible band, two side plates with projecting flanges, and means to clamp the parts in position when surrounding a conductor. The flexible metallic band may be formed of any suitable material, and the projecting end 4 of the same with the U-shaped extremity forms an integral terminal portion which 35 may be easily engaged with the end of a wire. The manner of applying this device to use and the operation thereof will be readily understood, and it will be seen that I have provided a simple, inexpensive, and

efficient means for carrying out the objects 40 of this invention. If desired, the flexible metallic band may be used as above described without the necessity of employing the side plates 8 and 9, as the said band would be adapted to securely engage the conductor 7 if held together only by the screw 13 and nut 14.

I claim as my invention:

In a device of the class described, a flexible metallic strip adapted to surround a 50 suitable conductor and having its end portions disposed adjacent each other with alined apertures therethrough, a projecting portion on one end of said strip to form a connecting terminal, side plates of equal 55 width and greater thicknesses than said strip positioned against the outer surfaces of the end portions and having apertures therethrough alining with the apertures through said ends, one of said plates having its apertures screw threaded, a locking screw 60 extending through the alining apertures in the plates and end portions and operatively engaging said threaded aperture in one of the plates, a lock nut on the outer end of the 65 screw adjacent said plate, and obliquely inclined outwardly extending spacing flanges projecting from the inner edges of said plates and adapted to space said plates from the conductor and to additionally clamp the 70 strip around the same.

In testimony whereof I have hereunto set my hand in presence of two subscribing witnesses.

ISRAEL MARCUS.
